2 Sheets-Sheet 2

UNITED STATES PATENT OFFICE.

JOHN M. KROLICK, OF BROOKLYN, NEW YORK.

MANIFOLDING MEANS.

Application filed July 20, 1922. Serial No. 576,225.

To all whom it may concern:

Be it known that I, JOHN M. KROLICK, a citizen of the Republic of Poland, and resident of Brooklyn, in the county of 5 Kings and State of New York, have invented certain new and useful Improvements in Manifolding Means, of which the following is a specification.

My present invention relates to manifolding and has its preferred specific application 10 to the typing of items concurrently upon a ledger and a statement sheet.

In the practice of business offices, it is desirable to file the ledger sheets with the corresponding 15 statement sheets intimately associated therewith, so that they can be inserted as a unit into a typewriting machine by a single operation, thus dispensing with the need for specially correlating or collating 20 the two sheets that are usually of different sizes.

It is among the objects of my invention to provide for the ledger and statement sheet, a correlating means of particularly simple 25 and inexpensive construction, which shall be easy to apply or adjust, yet effective to retain the sheets against relative displacement at all stages of the operation, which shall require no substantial alteration in the conventional 30 styles of ledger and statement sheets, which shall be economical of filing space and which shall have no parts that can readily become caught, loosened, torn or destroyed in use, as in the insertion into or in 35 the removal from the typewriter.

In the preferred embodiment of the invention, I provide a simple hanger element which may be of paper extending transversely of the statement sheet and straddled 40 thereby at a fold below the heading thereof, the ends of said hanger element projecting beyond the lateral edges of the statement sheet and being removably secured to the ledger sheet, preferably by threading each 45 end into a strip, formed by a pair of parallel slits.

In the preferred embodiment, the hanger element embodies in addition to the portion which is straddled by the statement sheet, an 50 integral clamping portion preferably straddling the statement sheet, said clamping portion being retained in effective holding position by the attachment of the hanger to the ledger sheet. In the preferred specific embodiment, the hanger comprises a simple rectangular strip transversely and longitudi-

nally folded to form an inner longitudinally folded hanger element or leg straddled by the statement sheet and a similar clamping member straddling the fold of the statement 60 sheet. The transfer sheet is preferably secured as by pasting to the hanger element.

In the accompanying drawings in which are shown one or more of various possible embodiments of the several features of the 65 invention,

Fig. 1 is a view of the face of a preferred form of ledger sheet,

Fig. 2 is a view of a double ledger sheet open, showing the statement and transfer 70 sheets applied in position,

Fig. 3 is a transverse sectional view on a larger scale taken along the line 3—3 of Fig. 2,

Fig. 4 is a perspective view of a preferred 75 hanger element,

Fig. 5 is a plan view of an alternative embodiment of ledger and support,

Fig. 6 shows an open distended view of 80 the alternative embodiment,

Fig. 7 is a perspective view of the hanger element and transfer sheet assembly shown in Fig. 6,

Fig. 8 is a transverse sectional view taken along the line 8—8 of Fig. 6, 85

Fig. 9 is a sectional view on a larger scale taken along the line 9—9 of Fig. 6, and;

Fig. 10 is a fragmentary view of a modification.

Referring now to Figs. 1 to 4 of the drawings, I have shown a ledger sheet of conventional construction and arrangement, including the heading portion 1, with space for the name and address of a customer and other usual items, said sheet also including a succession of vertical columns 2 with the usual titles, Pick up, Date, Items, Debits, Credits and Balance, indicated in the drawings. The second column 3 and the next to the last column 4 have no particular utility 90 in the ordinary ledger system. It is in the region of these columns that the correlating device is, therefore, preferably connected with the ledger sheet, as will appear herein-after.

The statement sheet in the present embodiment is of conventional construction, including a heading portion 5 and a body portion 6 having the usual vertical statement columns corresponding with the columns on the ledger sheet entitled Date, Items, Debits and Credits. The statement sheet is folded 105

as at 7 immediately below the heading portion 5, that is, at the head of the body or column section 6, and a transfer or carbon sheet is inserted therebetween and straddled there-
5 by.

If the fold 7 be retained along the line 9 at the head of the columns of the ledger sheet, with the statement sheet columns in registry with corresponding ledger columns,
10 the parts will obviously be disposed in correct relative position for typing an original upon the ledger and a carbon on the statement sheet.

To maintain the parts in the desired relative position, I provide a hanger member, a preferred embodiment of which is shown in Fig. 4. This hanger member is preferably formed of an elongated rectangular sheet of paper folded at its center transversely as at 10 and longitudinally as at 9 to form a pair of tongs having gripping jaws or legs 11 and 12, the lower or inner jaw constituting the hanger proper, which the statement sheet straddles at the fold 7.
15 The upper jaw 12 of the tongs constitutes a clamping member which, in turn, straddles the statement sheet and aids to maintain the same in firm position and against slipping. The hanger element is wider than the statement and transfer sheets, its end 13 at the hinging portion 10 and the free ends of both legs 11 and 12 projecting beyond the lateral edges of said sheet. A pair of transverse slits 15 are provided in the unused columns
20 3 and 4 of the ledger sheet adjacent the heads of the columns to form support strips 16 and the projecting ends 13 and 14 of the hanger are threaded through said strips, as best shown in Fig. 2, thereby supporting the statement sheet from the ledger sheet, and also firmly securing the jaws of the tongs together, to rigidly maintain the statement sheet against slipping with respect to the hanger, even under substantial pull. The
25 transfer or carbon sheet may be secured in a manner similar to the statement sheet, but preferably, it is pasted as at 17 to one part of the hanger element.

If desired, a similar hanger element 18
30 may be provided near the lower end of the ledger sheet for securing a statement sheet 19 projecting upward therefrom, the lower end of the upper statement sheet 6 overlapping the heading (not shown) of the lower statement sheet, so that in the entry of items, after the lower end of the upper statement sheet is passed, the succeeding entries will appear in the proper position beginning at the top of the columns of the lower statement sheet. The carbon or transfer sheet
35 8 is preferably of such length as to extend at least to the upper edge of the lower support or hanger element, as best shown in Fig. 3.

As will appear in the detail of Fig. 10,
65 if it is desired not to slit the ledger sheet, as in Fig. 2, for mounting the hanger, the projecting ends 13 and 14 of the hanger element may be secured in pockets on the ledger formed by tabs as at 20 adjacent but
70 beyond the lateral edges of the statement sheet, overlapping the projections 13 and 14 and secured preferably by pasting as at 21 near their upper and lower ends to the ledger sheet to form a sheath between said
75 pasted portions into which the hanger projection is inserted.

It will be seen that my ledger filing system is particularly inexpensive, convenient and effective. The statement sheet is modified from standard practice in no particular, and the ledger sheet is merely provided with the two sets of slits 15 or with the securing tabs 20. The hanger element is merely a simple rectangular sheet of paper or the equivalent transversely and longitudinally bent, to one of the legs of which, an ordinary transfer sheet may be pasted. The statement sheet is applied simply by straddling the inner jaw of the hanger tongs, the outer jaw acting as a clamp and the projecting ends of the hanger are threaded into the strips 16 as in Fig. 2 or inserted into the pockets formed by the pasted tabs 20 as in Fig. 10. The statement sheet is firmly held by the clamping tongs hanger against the possibility of slipping with respect thereto longitudinally of the ledger sheet, and the hanger element, in turn, is retained against slipping laterally of the ledger sheet by the coaction of the clamped fold of the statement sheet and the transfer sheet (pasted to the hanger) with the adjacent edges of the strips or tabs on the ledger. At the end of the month, the hanger with the statement and transfer sheets thereon is readily removed from the ledger sheet by withdrawing the hanger projections 13 and 14 from the strips 16 or sheaths 20 on the ledger, and the legs
90 11 and 12 of the hanger tongs may then be spread apart to remove the statement sheet and to replace it with a new one, the parts
95 being reassembled in the manner heretofore described.

Where a double ledger sheet, as shown in Figs. 1 and 2 is not desired, the arrangement shown in Figs. 5 to 9 may be employed to advantage. In this embodiment, is shown the ordinary single ledger sheet 22 indicated in Fig. 5, a backing sheet 23 of cheaper paper and preferably of the same area as the ledger being secured thereto by integral tongues 24 projecting from the upper edge thereof and threaded through corresponding strips 25 formed by slits 26 near the upper edge of the ledger sheet. Upon the backing sheet, the statement and transfer sheets may be mounted in the same man-
100
105
110
115
120
125

ner as in Figs. 1 to 4. I have however shown an alternative embodiment in which the hanger element comprises an elongated strip of paper, bent transversely in the middle as at 27 to form two legs 28 and 29 to one of which the transfer or carbon sheet 30 is secured by pasting as at 31, the statement sheet being folded below its heading in the usual manner and straddling said leg, the other leg being superposed over the statement sheet adjacent the fold. The projecting ends 32 and 33 of the hanger element serve for attachment to the backing or ledger sheet. In this particular embodiment instead of the longitudinal strips, shown in Fig. 2, I have shown a pair of diagonal strips 34 formed by corresponding slits 35, whereby the corners of the statement and transfer sheets will be threaded through said diagonal strips, the projecting ends 32 and 33 extending beyond the outer or lower edges 36 of the strips, with the lateral edges of the statement sheet against said edges 36.

It will thereby be seen that the clamping means is securely held in effective position by the strips 35 on the backing sheet, the projecting ends 32 and 33 of the supporting hanger element being confined by the lower ends 36 of the strips against downward movement of the hanger and statement, the latter being restrained against displacement transversely of the support sheet, not only by the ends 36 of the strips 35, but by the frictional hold thereon of the legs of the hanger.

It will thus be seen that there is herein described a means in which the several features of this invention are embodied, and which means in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters-Patent of the United States is:—

1. In combination, a main sheet, an auxiliary sheet and a transfer sheet of lesser width than said main sheet, a hanger element for one of said latter sheets extending transversely across and projecting beyond the lateral edges thereof, and means for securing said projecting ends to said main sheet.

2. In combination, a main sheet, an auxiliary sheet and a transfer sheet of lesser width than said main sheet, and a hanger

element sustaining said auxiliary and said transfer sheets, said hanger element having integral extensions, and means for securing said extensions to said main sheet.

3. In combination, a main sheet, an auxiliary sheet and a transfer sheet of lesser width than said main sheet, and a hanger element straddled by said auxiliary sheet and also sustaining said auxiliary and said transfer sheets, said hanger element having integral extensions beyond the lateral edges of said auxiliary and transfer sheets, and means for securing said extensions to said main sheet.

4. In combination, a support sheet, a statement sheet narrower than said support sheet and a hanger element extending transversely of said statement sheet, and extending beyond the lateral edges thereof, said statement sheet having a fold below its heading and straddling a portion of said hanger, and means attaching the projecting ends of said hanger to said support sheet.

5. In combination, a support sheet, a statement sheet of lesser width and a transfer sheet, a hanger element of greater width than said statement sheet, the latter straddling a portion of said hanger element with its heading reversely bent, means removably attaching the projecting ends of said hanger element to said support sheet, and means attaching the transfer sheet in proper relation to said statement sheet.

6. In combination, a ledger sheet, a statement sheet of lesser width and a transfer sheet, said statement sheet having a transverse fold, a hanger element straddling the part of said statement sheet at one side of said fold, means securing said transfer sheet with respect to said statement sheet, said hanger element having portions projecting beyond the lateral edges of said statement and transfer sheets, and means detachably securing said projecting ends to said ledger sheet.

7. In combination, a ledger sheet, a statement sheet of lesser width and a transfer sheet, said statement sheet having a transverse fold, a hanger element having a portion straddled by said statement sheet at said fold and having integral extensions beyond the lateral edges of said statement sheet, and means detachably securing said projections to said ledger sheet.

8. The combination set forth in claim 7 in which there is provided means to prevent displacement of said statement sheet away from said hanger.

9. In combination, a ledger sheet, a statement sheet and a transfer sheet, a hanger element, one end of said transfer sheet being fixed to said hanger element, said statement sheet being folded over an edge of said hanger element, said hanger element having means associated therewith for clamping

said statement sheet against said hanger element, and means for detachably securing said hanger element to said ledger sheet.

10. In combination, a support sheet, a statement sheet of lesser width and a transfer sheet, said statement sheet being folded below its heading over one portion of said hanger element, said hanger element including integral clamping means for retaining said statement sheet against displacement therefrom, said hanger element with its clamping means projecting beyond the lateral edges of said statement sheet, and means for securing said projecting ends to said support sheet.

11. In combination, a statement sheet and a hanger element separate and distinct therefrom comprising a strip straddled by said statement sheet and a clamping element straddling the fold of said statement sheet, said strip and clamping element extending beyond the lateral edges of said statement sheet for attachment to a support sheet of greater width than said statement sheet.

12. In combination, a ledger sheet, a statement sheet and a transfer sheet, a hanger element having an inner strip, said transfer sheet being secured to said strip, said statement sheet straddling said strip, said hanger element including a clamping portion in turn straddling said statement sheet, the hanger and its clamping portion projecting beyond the lateral edges of said statement sheet, and means on said ledger sheet co-acting with said projecting ends to mount said hanger and to maintain said hanger in clamped condition.

13. In combination, a ledger sheet, a statement sheet, a hanger element for supporting the latter from the ledger sheet, said hanger element including an elongated strip of paper or the like folded transversely and longitudinally to form tongs over the inner fold of which the statement sheet is hung and the outer fold of which clamps said statement sheet with respect to the inner fold, said hanger element projecting beyond the lateral edges of said statement sheet, and means for securing said projecting ends to said ledger sheet.

14. A hanger element in a ledger-statement filing system, said hanger element comprising an elongated strip transversely and longitudinally bent at its center to form an inner fold or hanger portion and an outer fold or clamp portion.

15. In a ledger system, in combination, a ledger sheet and a statement sheet, a hanger element having a portion straddled by said statement sheet and removable with respect thereto and projecting beyond the lateral edges thereof, and means for removably securing said projecting ends to said ledger sheet.

16. In a ledger system, in combination, a ledger sheet, a statement sheet of lesser width, a hanger element extending transversely of said statement sheet and projecting beyond the lateral edges thereof, and a strip in said ledger sheet for removably attaching said projecting ends of said hanger element.

17. In a ledger system, in combination, a ledger sheet, a statement sheet of lesser width, a hanger element extending transversely of said statement sheet and projecting beyond the lateral edges thereof, and tabs superposed over said projecting ends beyond the edges of said statement sheet and secured to said ledger sheet beyond the lower and upper edges of said projections.

18. In a ledger system, in combination, a hanger element, a statement sheet straddling a portion of said hanger element, said element including means clamping said statement sheet in position, means attaching said transfer sheet to said hanger element, said hanger element having ends projecting beyond the lateral edges of said statement sheet and short longitudinal strips in said ledger sheet for securing said projecting ends and maintaining the clamping portion of said hanger element in firm coaction with the straddled portion thereof.

19. In a ledger system, in combination, a ledger sheet, a statement sheet and a transfer sheet of lesser width, a hanger element comprising an elongated strip transversely folded to form two legs, said statement sheet straddling one of the legs of said hanger element, the other leg thereof serving as a clamping element, said hanger element extending beyond the lateral edges of said statement sheet, and means on said ledger sheet for removable attachment of said projecting ends, said means serving to clamp the two legs of said hanger element together.

20. In a ledger system, in combination, a support sheet, a statement sheet, a hanger element therefor, said hanger element including extensions beyond the lateral edges of said statement sheet, and diagonal strips in said support sheet through which said hanger extensions and the adjacent edges of said statement sheet are threaded, said extensions projecting beyond the outer edges of said strips.

21. In combination, a ledger sheet, a backing sheet attached thereto, a statement sheet, a hanger element therefor projecting beyond the lateral edges of the statement sheet, and means for detachably securing said projecting ends to said backing sheet.

Signed at New York in the county of New York and State of New York this 19th day of July, 1922, A. D.

JOHN M. KROLICK.
